UNITED STATES PATENT OFFICE

NATHANIEL E. LOOMIS, OF ELIZABETH, NEW JERSEY, ASSIGNOR TO STANDARD OIL DEVELOPMENT COMPANY, A CORPORATION OF DELAWARE

ART OF PRESSURE DISTILLATION

Application filed May 16, 1922. Serial No. 561,407.

This invention relates to the art of pressure distillation or pyrolytic conversion of heavy petroleum oils into lighter products, and particularly to improvements in methods and apparatus of the general character set forth in Patent 1,405,286. The invention will be fully understood from the following description taken in connection with the accompanying drawing which represents a side elevation, partly in section, of an embodiment of my invention.

Referring more particularly to the drawing, the letter A designates generally a pressure-still, preferably of the type comprising a horizontal cylindrical drum 1 and a bank 15 of tubes 2 connected thereto by legs 3, the tubes being mounted in a furnace fired by coal or by oil-burners as desired. Leading from the still is a vapor-connection 4 opening 20 into an intermediate drum 5 which may conveniently be of horizontal cylindrical form, and which contains baffle-spreaders 6 for a purpose to be referred to hereinafter, these preferably being of such construction and 25 mounting as to be readily removable, in order to facilitate cleaning of the drum when necessary. A vapor-connection 7 opens into a final drum 8 supported on a suitable mounting (not shown, for simplicity), and containing 30 a transverse tube-sheet 9 in which are tapped horizontal pipes 14 having small perforations for the escape of vapors, as will later be referred to in detail. Spaced from the tube sheet is a false-head 10 with a free 35 vapor passageway over its upper edge. Leading through the tube-sheet 9 and false-head 10 is an overflow pipe 11 which extends down through the vapor connection to terminate 40 within the distributor-trough 12, the pipe dipping beneath the liquid-surface sufficiently to form a seal against any possible back-flow of vapors from drum 8.

A feed-pipe 13 is tapped into the drum 8, 45 also a draw-off pipe 21; and a similar draw-off pipe may be provided in drum 5 if desired. The drum 8 thus can operate as a feed-oil container, and also perform further functions as will be shown hereinafter.

50 The drums are lagged with any suitable

layered, cellular or solid insulation 19, and are provided with manheads.

Leading from the drum 8 is a vapor-line 16 connecting with a water-cooled condenser 17, and the usual receiver equipment, shown conventionally at 18.

The usual equipment of gauges, pyrometers, release and safety valves, etc., is applied throughout the system.

Using the apparatus above described, the procedure may be as follows:

The still is charged, usually with gas oil, and is fired at the start under atmospheric pressure until any traces of water or light hydrocarbons pass over. These so-called "drips" may be directly continuously drained out from drum 8 by the pipe 21; and having been eliminated, the drain-valve is then closed and the receiver may now be connected in on the high-pressure gas manifold, 55 where stills are being operated in a battery, and the gas passing back through the vapor-line 16 and check-valve 20 will initially provide the necessary operating pressure, for example 95 lbs. gauge-pressure. The firing of the still can now be pushed until the oil temperature reaches about 725° F. or more. At first, the vapors coming up from the still will almost wholly condense in the drums, the heaviest fractions and liquid or mist particles 60 swept along by the vapors dropping out especially in drum 5, the remaining vapors then passing on into drum 8. The vapors then displacing the accumulating oil between false-head 10 and tube-sheet 9 enter the tubes 70 14 and escape by bubbling up through the accumulating liquid body.

A temperature level is presently reached where only relatively heavy hydrocarbons are condensed and retained in the oil body, while the gasoline vapors are allowed to pass on through the vapor-line 16 to the water-cooled condenser 17 and the receiver. As the condensation in the drum 8 adds to the liquid, 75 overflow begins down through pipe 11. The desired running conditions having now been established, feed-stock, which may be a gas oil of the same or a lighter gravity is supplied by the feed line 13 and at such rate as to compensate for the distillate being taken off at 100

the receiver, so as to maintain the volume in the system constant, and the run is so continued until it is necessary to stop for cleaning. The overflow, consisting of feed-stock and heavy condensates, passing down by pipe 5 11 distributes from trough 12 so as to flow down the spreaders 6 in a comparatively thin film where it is heated both indirectly by the bottom heat of conduction through the 10 spreader plates from vapors passing underneath, and especially, directly by the vapors passing over the thoroughly exposed surface. Any lighter constituents held are thus here re-vaporized and released to pass on to the condenser system, and the remaining liquid flows 15 on down to the still, being sufficiently heated first in drum 8 and finally in drum 5 to enter the still without a retardant cooling of the charge therein. At the same time the vapors 20 fresh from the still entering drum 5 drop out their heaviest constituents to reflux to the still, likewise entrained liquid particles carried up from the still by the rush of vapors.

As a result of all this, the final drum 8 is 25 kept free from the heaviest reflux, and also runs at such a temperature level that it is enabled to effect a relatively close final separation.

As a further means of adjusting the temperature in drum 8, there is provided a coil 15, 30 through which may be circulated a cooling medium, such as an oil of suitable temperature, or preferably water.

The initial detail of operation may be modified slightly, if desired, by charging both 35 drum 8 and still 1 at the start. After firing as usual and putting the still up to running pressure and temperature, the vapors reaching drum 8 displace the liquid between the 40 false-head 10 and tube-sheet 9, and enter the tubes 14 and escape by bubbling up through the oil. As the oil warms up, a temperature level is reached, where only heavier hydrocarbons are condensed and retained in the oil 45 body, while the gasoline vapors are allowed to pass on over to the condenser 17. As the condensation in the drum 8 adds to the liquid and starts the overflow down through pipe 11, the supply of feed stock is begun through 50 the feed line 13 at such rate as to compensate for the volume of distillate leaving the system, this and the further detail being as above mentioned.

While in describing my invention I have 55 referred to particular details, it will be understood that this is for the purpose of illustration and explanation, and in no sense limitative, nor is it dependent upon the accuracy of the theories or reasons which I have advanced to account for the advantageous results attained, but the invention is to be regarded as limited only as defined in the following claims in which it is my intention to claim all inherent novelty as broadly as the 60 prior art permits.

What I claim is:—

1. A petroleum distilling apparatus which comprises a still, means for exposing films of incoming feed-oil to the outgoing vapors, a feed-oil container, means for bubbling the vapors through the oil in such container and means for controlling the temperature of the oil in said container. 70

2. A petroleum distilling apparatus which comprises a still, a series of baffle-spreaders in the path of the outgoing vapors and the incoming feed-oil, a feed-oil container, means for bubbling the vapors through the oil in such container and a cooling coil in said container. 75

3. A petroleum distilling apparatus which comprises a still, a drum for receiving vapors from the still and containing staggered baffles for exposing films of feed-oil to the vapors, and a further drum for containing an overflow body of oil into which the vapors are successively bubbled. 80

4. A petroleum distilling apparatus, which comprises a still, a drum for receiving vapors from the still and containing staggered baffles for exposing films of feed-oil to the vapors, a further drum for containing an overflow body of oil into which the vapors are successively bubbled, and means for introducing feed-oil into said last-named drum. 90

5. A petroleum distilling apparatus which comprises a still, a feed-oil container, a submerged inlet for admitting still-vapors thereinto, means for controlling the temperature of said container and a series of staggered baffles interposed in the path of the vapors between said still and said container. 95

6. A petroleum distilling apparatus which comprises a still, a heat insulated feed-oil container, a submerged inlet for admitting still-vapors thereinto, a temperature-controlling coil in said container and a series of staggered baffles interposed in the path of the vapors between said still and said container. 100

7. A petroleum distilling apparatus, which comprises a still, a drum for receiving the vapors from the still and containing a series of baffle-spreaders to carry a film of oil, a distributor-trough on the uppermost of said baffles, a feed-oil container into which the vapors are successively bubbled, an overflow pipe from said container dipping into said distributor-trough, means for supplying feed-oil to said container, and means for controlling the temperature of said container. 110

8. A petroleum distilling apparatus, which comprises a still, a drum for receiving the vapors from the still and containing a series of baffle-spreaders to carry a film of oil, a distributor-trough on the uppermost of said baffles, a feed-oil container into which the vapors are successively bubbled, an overflow pipe from said container dipping into said distributor-trough, means for supplying feed- 120

oil to said container, and a temperature-controlling coil in said container.

9. Improvement in the art of pressure distillation of petroleum oils for the purpose of producing lighter products which comprises passing the rising vapors over counter currently flowing films of oil, thereby separating out and refluxing the heaviest portions of the vapors, bubbling the remaining vapors through a body of oil, and positively cooling the said body of oil to control the character of vapors escaping therefrom.

10. Improvement in the art of pressure distillation of petroleum oils for the purpose of producing lighter products which comprises passing the rising vapors over counter currently flowing films of oil, bubbling the remaining vapors through a body of oil, a part at least of which is provided by introduction of feed stock and positively cooling the said body of oil to control the character of vapors escaping therefrom.
